UNITED STATES PATENT OFFICE.

ALICE MARGARETT ANDREWS, OF WHEELING, WEST VIRGINIA.

SIGHT FOR GUNS.

SPECIFICATION forming part of Letters Patent No. 763,348, dated June 28, 1904.

Application filed June 10, 1903. Serial No. 160,913. (No model.)

To all whom it may concern:

Be it known that I, ALICE MARGARETT ANDREWS, a citizen of the United States, residing at Wheeling, in the county of Ohio and State of West Virginia, have invented a new and useful Sight for Rifles, of which the following is a specification.

My invention is an improvement in a sight for rifles.

10 The objects of my improvements are to provide a sight having lateral and vertical adjustment.

15 My invention consists of the novel features and combination of parts described hereinafter, particularly pointed out in the claims, and shown in the accompanying drawings.

20 In the drawings forming part of this specification, Figure 1 is a side elevation of a rifle, showing my improvement in position. Fig. 2 is a plan view of the sight-piece. Fig. 3 is a horizontal section taken through the sight-opening. Fig. 4 is a front elevation, the supporting-bar being in section. Figs. 5, 6, 7, and 8 are perspective detail views showing 25 parts of the sight detached. Fig. 9 is a plan view of the sight-supporting bar. Fig. 10 is a side elevation of the supporting-bar. Fig. 11 is a vertical section taken at a right angle to that in Fig. 3. Figs. 12 and 13 are perspective views of the sight, the parts being assembled, as seen from different points.

30 In applying my improved sight to a rifle I cut two transverse dovetail grooves A in a rifle-barrel A'. A supporting-bar B, formed 35 of a piece of thin metal, preferably steel, has its rear half B' offset, so as to throw it above the plane of the forward portion, and at the rear end supports a rectangular frame B², the frame having upper and lower laterally-extending perforated lugs B³. On the under 40 surface of the part B are formed dovetailed tongues B⁴, fitting into the dovetail grooves A and holding the bar B firmly on the rifle-barrel, the offset portion B' extending rearwardly over the stock and raised sufficiently 45 above the flange of the barrel to clear the hammer A². A rectangular plate C is provided, having forwardly-projecting perforated ears C⁷ and a rearwardly-projecting block portion C⁸ and also having a laterally-

and rearwardly extending lug C³, vertically perforated. An opening C⁴, oval in cross-section, passes through the block C² and plate C. A rectangular block D is formed with a threaded opening D', and above the opening, midway the ends of the block, is a lug D², having a threaded opening D³ at right angles to the opening D'. In assembling these various parts, which together constitute the sight-carrying frame, the plate C is placed on the portion B' of the supporting-bar resting against the frame B², the block C² extending within the frame. The lug C³ rests immediately above the lower lug B³, and a screw B⁵ extends through the perforations of the lugs B³ and works in 55 the threaded perforation of the lug C³. The block D fits against the front face of the plate C, and a screw C⁶ passes through the ears C' and works in the threaded opening D³, a washer C⁶ being on the screw adjacent one of the ears 60 C'. A bell-mouth E has an exteriorly-threaded stem E', the said stem having a conical aperture E². The end of the bell-mouth rests adjacent the rear of the frame B² and block C², and the threaded stem projects through the 65 opening C⁴ and works in the threaded opening D'. As the opening C⁴ is horizontally elongated, the stem E' has lateral movement therein. By turning the screw C⁶ the block 70 D will be caused to slide laterally on the face of the plate C², moving the stem and bell-mouth with it. By adjusting the screw B⁵ the plate C will be moved vertically, carrying the block C² and the other parts with it. It 75 will be understood, therefore, that the block C² has vertical movement in the frame B² and that the block D has lateral horizontal movement between the ears C'. 80

Having thus fully described my invention, what I claim as new, and desire to secure by 90 Letters Patent, is—

1. The combination with a rifle-barrel, of a rectangular frame supported from said barrel, a block adjustably held in said frame, a second block adapted to slide longitudinally in 95 advance of the first-mentioned block, and a sight-piece supported by and adapted to move with the block.

2. The combination with a rifle-barrel, of a supporting-bar secured thereto and projecting 100

over and above the rifle-stock, a vertical rectangular frame carried by said bar, a plate having a block adapted to slide vertically in the frame, a block sliding longitudinally on 5 the front face of the plate, and a sight-piece supported by and moving with the plate and blocks.

3. A device of the kind described, comprising a supporting-bar, a rectangular bar, open 10 frame carried by said bar, a plate having a block portion extending rearwardly therefrom, said block portion fitting and sliding in the frame, said plate and block having a transverse opening therethrough, forwardly-projecting 15 ears carried by the plate, a block having a threaded bore alining with the opening in the plate, said block sliding between the ears of the plate, and a bell-shaped sight-piece having a perforated, threaded stem, said stem 20 passing through the opening and working in the bore of the last-mentioned block.

4. In a device of the kind described, a rectan-

25 gular frame having laterally-extending perforated, upper and lower lugs on one side, a plate having forwardly-projecting ears and a laterally and rearwardly extending lug having a threaded perforation therein, and a rearwardly-extending block sliding in said frame, 30 said plate and block having an opening formed therein, a threaded screw passing through the lugs above mentioned, a block having a threaded bore alining with the opening in the plate and having a lug with a threaded bore transverse to the bore in the block, a screw extending through the ears of the plate and working 35 in the bore of the lug, and a sight-piece having a threaded stem extending through the opening in the plate and first-mentioned block and working in the bore of the last-mentioned block.
